UNITED STATES PATENT OFFICE.

JOHN A. SMITH, OF BALTIMORE, MARYLAND, ASSIGNOR TO SMITH LYRAPHONE COMPANY, A CORPORATION OF WEST VIRGINIA.

AUTOMATIC ATTACHMENT FOR PIANOS.

SPECIFICATION forming part of Letters Patent No. 761,419, dated May 31, 1904.

Application filed March 12, 1902; Renewed October 31, 1903. Serial No. 179,409. (No model.)

To all whom it may concern:

Be it known that I, JOHN A. SMITH, a citizen of the United States, residing at Baltimore, in the State of Maryland, have invented certain new and useful Improvements in Automatic Attachments for Pianos, of which the following is a specification.

This invention relates to improvements in automatic attachments for pianos.

10 The object of the invention is to provide a simple and efficient means for automatically operating the key-levers of a piano.

The invention consists of the new and novel parts and combination of parts hereinafter 15 shown, described, and pointed out in the claims.

In the accompanying drawings, illustrating my invention, in the several figures of which like parts are similarly designated, Figure 1 20 is a front elevation of a portion of my apparatus with the casing partly broken away to show the interior mechanism. Fig. 2 is plan view of a portion of my apparatus with the top of the casing removed, showing the interior mechanism. Fig. 3 is a side elevation, partly in section, showing the keyboard-operating devices and their connected operating means. Fig. 4 is a side elevation, partly in section, showing the tempo or time controlling mechanism and other parts. Fig. 5 is 25 an enlarged detail view showing in part one of the composite fingers for operating the keyboard-operating devices or levers. Fig. 6 is an enlarged detail, in bottom plan view, of portion of the wind-chest and its attached operating-wires. Fig. 7 is a detail view showing a thumb-piece for operating the tempo or time controlling mechanism. Fig. 8 is a detail view showing the application of an electric motor for driving the shoe-lever-operating cylinder and other parts of the apparatus. Figs. 9 and 10 are enlarged detail views showing a sliding lock for holding the expression-lever or finger-piece in its adjusted positions.

40 In carrying out my invention I provide a series of keyboard-operating devices or levers comprising a series of levers 1, 2, and 3, and as such levers are the same throughout the entire set of keyboard-operating devices I

have shown in the drawings one set thereof 50 only. (See especially Figs. 4 and 6.) The levers 1 are suitably supported from the casing of the apparatus, and each of said levers is pivoted at about its center and adapted at one end to engage the keys of the piano. 55 Connected to the other ends of the levers 1 by a flexible connection 4, such as a strip of leather or cloth, are the levers 2, and to the under sides of the levers 2 the levers 3 are connected by a piece of thin flat spring metal 60 5. The levers 3 are provided with a curved surface next adjacent the lever 2 for a purpose presently appearing. Secured to the lower end of levers 3 and depending therefrom is a curved arm 6, of wire or other suitable material, and said arm 6 terminates in a head 7. The series of levers 1, 2, and 3 as thus constructed and jointed together I will herein designate as "composite fingers," and they will hereinafter be so referred to as such. 70

Within the casing of the apparatus is suitably supported in uprights 8 a longitudinal bar 9, having an inclined surface 10, and upon this inclined surface 10 there are secured a series of head-blocks 11, equal in number to the 75 number of composite fingers. To the upper end of these head-blocks 11 the levers 3 of the composite fingers are pivoted, as at 12, and which levers 3 normally rest upon said head-blocks. To the lower ends of the head-blocks 80 11 are pivoted the levers 13, provided with the stops 14, engaging an extension 15 on the bar 9. The outer and extreme ends of the levers 13 are connected to and are operated upon by the puppets 16, arranged in suitable guides 85 17, the upper ends of said puppets being connected with rock-wires 18, (see Fig. 7,) arranged below and in line with the pneumatics 19 of the wind-chest 20. Loosely hung to the levers 13, as by pivots 21, are the shoe-levers 22, carrying at their lower ends the shoes 23, provided on their under surfaces with a padding 24, preferably constructed of cork, whereby a better frictional surface is obtained for a purpose presently appearing. 90 The shoe-levers 22 are also provided with frictional surfaces 22^a, upon which impinge the heads 7 of the curved arms 6 and through

which motion is communicated to the composite fingers for operating the keys of the piano. The frictional surfaces of the shoes 23 24 constitute perfect arcs of circles of which 5 the pivots 21 are the centers, and said surfaces are covered with the cork padding excepting the extreme toes 25, which are left uncovered and are polished. The shoes 23 are adapted to be depressed into contact with 10 the cylinder 26, mounted in bearings in the uprights 8 and adapted to be continuously rotated and constructed of a body or core of metal 27, wound with twine or cord 28, saturated with glue and a covering of cork 29, glued to the fibers of the twine and turned 15 perfectly true in a lathe. These cork surfaces of the shoes and cylinder are especially adapted to furnish the greatest tractive power with the least pressure, whereby a forcible action 20 is produced in the composite levers, and thereby a forcible touch of the levers 1 with the piano-keys is obtained.

The levers 13 are forced upward and held 25 in their normal inactive position by springs 29, suitably supported upon a cross-piece 30, mounted in the casing, and stops 31 are also secured in said cross-piece 30 and adapted to limit or govern the downward movement of 30 the levers 13. The stops 31 are preferably made adjustable in the cross-piece 30 for the purpose of regulating the action of the levers 13.

An expression-bar 32 is suitably supported 35 by means of spring-hinges 33 from an upright extension of the bar 9 and overhangs the levers 2 of the composite fingers and normally is held above said levers by its spring-hinges, and said expression-bar is provided with an operating-rod or finger-piece 34, extending to 40 the front of the casing in convenient reach of the operator, and by raising said finger-piece 34 vertically to bring the expression-bar 32 in closer proximity to the levers 2 the flexure of the connection between the levers 2 and 3 45 is reduced and a more direct action of lever 3 to the lever 1 is produced, and thereby a louder tone obtained. By this means it will be observed that expression in a piece of music can easily be produced by simply manipulating the finger-piece at the proper times.

The mechanism for rotating the cylinder 26 and operating the bellows 35 (see Figs. 1 and 4) consists of the main shaft 36, carrying the driving-pulley 37 and a crank 38. A belt 39, 55 adapted to communicate motion from the periphery of the driving-pulley 37 to the rotating cylinder 26 through its pulley 40, fastened upon its shaft, and a crank 38 to operate the bellows 35 through the pitman 41, the main shaft 36 deriving its motion, which should be of suitable uniform speed, from any available source of power.

While the cylinder 26 and the bellows 35 should have a uniform rate of speed, the music- 65 sheet 42 must travel at a variable speed, gov-

ernable for tempo effects, and to produce tempo effects the take-up rolls 43, upon which the music-sheet 42 is wound as it is drawn from its spool 43^a over the tracker 44, is provided at one end with a pulley 45, adapted to be engaged by and receive motion from the small pulley 46 on the shaft 47, whose opposite end carries the pulley 48, operated by the belt 49, having frictional contact with and receiving its motion from the disk-face 50 (see Fig. 1) of the driving-pulley 37. A pressure-pulley 51, drawn by a spring 52 toward the pulley 37, serves to firmly press the belt 49 against the disk-face of pulley 37. The pressure-pulley 51 has a wide face equal to the distance from near the shaft 36 to the periphery of the pulley 37 and is carried upon a swinging-bracket 53, suitably hung in the casing. The belt 49, moving in the direction indicated by the arrows, Figs. 1 and 4, is guided by a shifter 54, having an eye 54^a engaging said belt to any position along the disk-face of the pulley 37, either near the shaft 36, where its motion is very slow, or away from it, where its motion is increased. The shifter 54 is connected with and operated by the tempo-lever 55, suitably located at the front of the casing and pivoted within the casing and extending through an elongated opening 55^a therein and connected to the shifter 54 by means of a sliding rod 56 and an adjustable connection 56^a. The disk-face of the pulley 37 is covered with leather or other suitable material adapted to exert tractive power upon the belt 49.

The take-up or winding-roll pulley 45 and its engaging drive-pulley 46 are preferably frictional, although gear-wheels might be substituted therefor. The shaft 47 has a swinging bearing 47^a (see Fig. 4) near the pulley 46, held in engagement with the pulley 45 by a spring 56^b. A governing-stop 57, connected to a pivoted lever 58, having its free end impinging between the pulley 59 on the frame and a pulley 60 on the swinging shaft 47, is adapted to be pushed in when the travel of the music-sheet 42 is to be stopped and is pulled out when started. The operation of the stop 57, if pushed in to its limit, is to move the pulley 46 out of engagement with pulley 45 and hold it there; but if the stop be only partly pushed in the spring 56^b will force the engagement of the pulleys again as soon as the hand is moved from the stop. The governing-stop 57 not only serves the purpose of starting and stopping the travel of the music-sheet 42, but having been pushed in to its limit is adapted to be moved sidewise to bring into action the rewinding mechanism, which comprises a pulley 61, loosely mounted on the shaft 47 next the pulley 48, a coil-spring 62 being interposed between said pulleys to keep them a suitable distance apart. A belt 63 connects the pulley 61 with a pulley 64, fast on a shaft 65, suitably mounted in the frame. To the 130

other end of said shaft 65 is secured a pulley 66, communicating a reverse or rewinding motion to the roll-carrying bracket 67 through a belt 68 and pulley 69. The pulleys 48 and 61 are provided on their adjacent faces with lugs or projections 48^a and 61^a, respectively, adapted to engage one another when the pulley 61 is forced toward the pulley 48 by means of a push-piece 70 engaging the hub of said pulley 61, the said push-piece being connected to one end of a rock-shaft 71, suitably arranged in bearings 72 72 in the casing or frame, the other end of said rock-shaft being connected by a connecting-rod 73 with the stop 57, whereby upon moving the stop 57 laterally the rewinding mechanism is set into operation. The sidewise movement of the stop 57 is prevented, except when the stop is pushed in to its limit, by a stop 74 in the connecting-rod 73 engaging a lug 75, attached to a fixed or immovable part of the case or frame. (See Fig. 2.)

Just above the tempo-lever 55 and in close proximity to it I provide a lever 76, secured to the front of the case, and which I term a "hold." Its function is when pressed against the case to engage a rod 77, extending through the case, and which is connected with the lever 58, engaging the swinging bearing of the shaft 47, and thus slightly moves the pulley 46 out of engagement with the pulley 45, temporarily stopping the take-up roller, and consequently the travel of the music-sheet, so long as the hold 76 is pressed back and without stopping the sheet-winding mechanism. The spring 56^b forces the engagement of the pulleys again, and the movement of the music-sheet resumes as soon as the pressure upon the hold is removed.

The tempo-lever 55 may be rigidly fastened to the rod 56 of the shifter and move bodily with it to the right or the left in the operation of shifting the belt 49; but I prefer the form and means of connection shown in Fig. 2, the tempo-lever being fulcrumed to the frame at its rear end and attached by a connecting-rod 56^a to the shifter-rod 56, approximately near its center, thus giving the forward end greater range of sidewise movement, requiring less force to operate it and insuring greater delicacy in governing the tempo.

For convenience in controlling the operations or manipulations of the tempo-lever 55, the expression-lever 34, and the hold 76 I group or arrange them near together at the front of the apparatus, as shown in Figs. 1, 2, 3, and 4, the tempo-lever being adapted to be swung to the right or left by the thumb supported in the U-shaped thumb-rest with the expression-lever underneath having vertical movement, the spring of the expression-bar keeping it (the expression-lever) normally in its lowest position for soft tone and adapted to be moved upward by a finger for louder

tone and the hold just above the tempo-lever and within easy reach of the thumb when it is desired to effect a hold or pause. I also provide an auxiliary expression-lever 78, which operates a slide 79 on the inside of the front board of the case, (shown in detail in Figs. 9 and 10,) said slide having an inclined edge 80, on which the expression-lever 34 may be made to rest at any desired position for the purpose of producing uniform tones of medium volume or any between the softest and the loudest of the instrument being played upon.

It will readily be understood from the foregoing description of the action of the expression-bar 32 upon the levers 2 that instantaneous changes from soft to loud, or vice versa, or any shading of the accent and expression may be produced by the proper use and manipulation of the expression-lever 34.

Each of the series of pneumatics 19, one for each key to be operated and each in line with its respective key, is reached by the outside air to inflate it through a hole in the foundation or top board of the wind-chest 20, on the under side of which the pneumatics 19 lie. On the top side of this wind-chest 20 a removable duct-board 81 is screwed, having a series of holes coincident and communicating with the holes through the foundation-board leading to the pneumatics.

The tracker 44 embodies a series of apertures 44^a, in number equal to the number of pneumatics to be inflated by the passage of air through them and arranged on a scale to correspond with the several lines of perforations in the music-sheets that are to be used. In the face of the tracker over which the music-sheet passes these apertures 44^a are quite narrow, increasing in width until the opposite side is reached, when they are about as wide as long. (See Figs. 8 and 14.) The several apertures are separated by very thin wedge-shaped partitions 44^b. Into the lower portion of each aperture a flexible tube 82 is cemented, and thence carried to and cemented in its corresponding hole in the duct-board 81, thus securing free and independent passage of the outer air to each pneumatic through its respective aperture 44^a, duct 82, and holes through duct-board 81 and foundation-board 20, governable by the travel of the perforated music-sheet 42 over the tracker 44. The tracker 44 is rigidly maintained in its proper position laterally and with reference to its height by the supports 83 secured to it, their lower ends being screwed to the duct-board 81, the forward side of the tracker resting against the board 84, which is a longitudinal part of the roll-frame.

The music-sheet 42 and its spool 42^a and the take-up roll 43 rest in the frame 85.

To provide means for playing the several kinds of music cut to any one scale, but varying as to their compass, I make the pianista

to embrace all the keys used in playing the music having the greatest compass, and in addition I include one or more notes both above and below to permit transposition without the loss of any of the higher or lower notes. For the notes above and below the range of such music as has a smaller compass I make a slide cut-off valve 88 in the duct-board 81, each being individually independent, and having a stop connection 88^a for closing or opening the air passage or passages, as shown in detail in Fig. 10.

In Fig. 1 I have shown a relief-valve 92 for relieving the apparatus of pressure of the bellows during the rewinding of the music-sheet. The valve 92 is connected to and adapted to be opened by the rock-shaft 71 of the shifting mechanism for the pulley 61 in the operation of rewinding. The valve 92 is held to its seat to close the relief-opening in the wind-chest by a spring 93.

The operation of my apparatus may be described briefly as follows: Power being applied to rotate the cylinder 26 in the direction of the arrow (see Figs. 1 and 3) and to start the wind apparatus, the shoe-levers are depressed into contact with said cylinder and set into operation the keyboard-operating levers through the medium of the composite fingers, as will be already understood from the above description. When the shoes come into contact with the cylinder rotating in the direction indicated by the arrow, they being forced into such contact by the pneumatics acting on the rock-wires 18, which in turn exert their force on the puppets 16, thereby depressing the levers 13, carrying the shoe-levers 22, the said shoe-levers communicate their motion to the composite fingers, and thereby actuate the keys of the piano. When motion is communicated to the shoe-levers 22 caused by the shoes 23 coming into contact with the revolving cylinder 26, the curved arms 6 will be raised, which in turn raise the levers 3. As the levers 3 move upwardly they carry the levers 2 with them, causing the rear ends of the said levers 2 to impinge against and raise the front ends of the levers 1, thereby forcing the rear ends of the latter down against the keys of the piano. It will be seen that as the flat metal spring 5 is connected by one end to the under surface of the levers 2, and by the other end to the upper surfaces of the levers 3, the front ends of the levers 2 are free to move up and down, the movement of the said front ends being governed by the expression-bar 32, which determines the force of the blow of the levers 1 upon the keys of the piano—that is to say, when the greatest degree of force upon the piano-key is desired the bar 32 is held firmly down upon the front ends of the levers 2 by means of the finger-piece 34, thereby allowing only the rear ends of the levers 2 to be raised; but when the bar 32 is raised the front ends of the levers 2 are then

held in position only by the tension of the springs 5, which latter then govern the force with which the levers 1 strike the piano-keys. The degree of force with which the levers 1 strike the keys of the piano decreases according to the distance the bar 32 is raised from the levers 2. After an action of the pneumatic and of the other parts resulting therefrom, as just described, the lever 13 is returned to its normal position by the force of the spring 29, lifting shoe-lever 22, and thus releasing shoe 23 from contact with the cylinder, when by their own gravity and the operation of the piano-action shoe 23 and the elements of the composite fingers also resume their normal positions, and the mechanism is ready for a repetition of the operation.

It will be observed that the levers 1 of the composite fingers are pivoted or fulcrumed near their centers, their rear arms extending over the keys they are to operate, while their forward ends rest upon and receive impulse from the levers 2, as shown. These levers 2 supply the elastic quality of the composite fingers, as shown in Fig. 6. The flexible connections or springs 5 are attached to the under sides of the levers 2 near their rear ends, thence extending forward, their forward ends secured to the coöperating lever 3. These springs are adjusted to hug the under side of their levers 2 with sufficient force only to cause a light elastic stroke to the lever 1 and through them to the keys of the piano with a gentle touch, but with sufficient force to produce a clear tone.

When the apparatus is operated, driven either by a crank attached to the shaft 36 or by the electric motor, (shown in Fig. 11,) the operator places the thumb in the thumb-rest of the tempo-lever 55, a finger under the expression-lever 34, the hold 76 being within easy reach of the thumb to effect a short pause in the travel of the music-sheet, in which position he has perfect control with one hand of the several devices for governing the expression, tempo, and hold. The stop 57 for starting, stopping, and rewinding may be manipulated by either hand. This operation is independent from expression or tempo.

Any degree of force or stroke between the extremes may be obtained by moving the expression-lever to the position giving the desired result and maintaining it there by slide 79, controlled by lever 78.

If the operator wishes to give accent and expression to the music, it may be done by keeping the finger on the expression-lever and governing the force of each succeeding tone or chord, as taste and judgment may dictate.

The desired effects in the music being played may be produced according to the feeling of the operator, or they may be produced by reading the marks of expression on a copy of the piece of music being played by the attachment.

In Fig. 8 I have shown an electric motor 94 for driving the cylinder 26, said motor being suitably mounted in bearings attached to the casing and located directly beneath the base-board of the casing and connected with a pulley 95 on the end of the cylinder by means of a belt 96 engaging a pulley 97 on the motor-shaft. The cylinder 26 is provided with adjustable bearings 98, whereby it may be adjusted with relation to the shoes 23 to secure proper contact of said shoes with the cylinder. A crank-rod 99 extends from the front of the casing to the rear thereof and is provided with suitable connections with the key-levers 15 for raising said key-levers away from the keyboard when it is desired to remove the attachment from the piano, whereby injury to the key-levers and their attachments is avoided.

The tempo-lever 55, as herein shown, is provided with a U-shaped thumb-piece, either constructed integrally therewith, as shown in Figs. 1 and 2, or made as a separate piece pivoted thereto, as shown in Fig. 9 and as hereinbefore described, and I wish it to be understood that said tempo-lever and its U-shaped thumb-rest not only serve the purpose of shifting the tempo mechanism, but also serve as a support for the hand, the thumb resting thereupon when the fingers are being used to manipulate the other parts of the apparatus.

All the new and novel parts and combination of parts herein shown and described, but not claimed, are made part of and are claimed in a separate application filed March 12, 1902, Serial No. 97,836.

Having thus described my invention, what I claim is—

1. In an automatic attachment for pianos, keyboard-operating devices constructed as composite fingers, comprising a series of levers 1, 2, and 3, and a flat metal spring 5, having one end secured to the lever 2 and the opposite end secured to the lever 3, and normally impinging against said levers 2 and 3 throughout its entire length, substantially as described.

2. In an automatic attachment for pianos, keyboard-operating devices constructed as composite fingers, comprising a series of levers, 1, 2, and, 3, and a flat metal spring 5, having one end secured to the under surface of lever 2, at or near the rear end thereof, and the opposite end secured to the upper surface of lever 3, at or near the front end thereof, substantially as described.

3. In an automatic attachment for pianos, the combination with the keyboard-operating devices, constructed as composite fingers 1, 2, and 3, and spring 5, between said levers 2 and 3, of an expression-bar 32 arranged above the levers 2; and a lever 34 connecting said expression-bar and extending through the front 65 of the casing, substantially as described.

4. In an automatic attachment for pianos, keyboard-operating devices constructed as composite fingers, comprising a series of levers 1, 2 and 3, and flexible connections for said levers, the said lever 3 being provided with a curved active face adjacent the lever 2, substantially as described.

5. In an automatic attachment for pianos, the combination with the cylinder 26 and the shoe-levers 22 23, of keyboard-operating devices constructed as composite fingers, comprising a series of levers 1, 2 and 3, and flexible connections therefor, and a depending arm secured to the lever 3, and adapted to impinge against said shoe-levers, substantially as and for the purpose described.

6. In an automatic attachment for pianos, the combination with the cylinder 26, the shoe-levers 22 23, and means for causing the shoes of said shoe-levers to contact with said cylinder, of keyboard-operating devices constructed as composite fingers, each comprising a series of levers 1, 2 and 3, and flexible connections therefor, and a depending arm secured to the lever 3 and adapted to impinge 80 against said shoe-levers, substantially as described.

7. In an automatic attachment for pianos, the combination with the keyboard-operating devices, constructed as composite fingers, comprising a series of levers 1, 2 and 3, and flexible connections therefor, and the cylinder 26, and shoe-levers 22, for operating said fingers, of an expression-bar arranged above the levers 2 and adapted to limit the movement of 100 said levers, substantially as described.

8. In an automatic attachment for pianos, the combination of the cylinder 26; keyboard-operating devices constructed as composite fingers, each comprising a series of levers 1, 2 and 3, and flexible connections therefor; depending arms 6 secured to the levers 3, and adapted to impinge against the shoe-levers; and an expression-bar 32 arranged above said levers 2 adapted to be adjusted with relation thereto to limit the movement of said levers, substantially as described.

9. In an automatic attachment for pianos, the combination with the keyboard-operating devices, constructed as composite fingers, each comprising a series of levers 1, 2 and 3, flexible connections therefor, and means consisting of the cylinder 26, shoe-levers 22, and depending arms 6, for operating said composite fingers, of an expression-bar arranged above the levers 2, and a finger-piece connected to said expression-bar extending through the front of the casing, whereby said expression-bar may be adjusted with relation to the levers 2 to limit the movement of said levers, substantially as described.

10. In an automatic attachment for pianos, the combination of the cylinder 26; shoe-levers 22; depending arms 6; keyboard-operating devices constructed as composite fingers, 130

consisting of a series of levers 1, 2 and 3, and a flat spring connecting the levers 2 and 3; and an expression-bar 32 arranged above and adapted to limit the movement of the levers 5 2, substantially as described.

11. In an automatic attachment for pianos, the combination with the sheet-winding mechanism and means for permanently stopping and restarting the same, of a lever 77 having 10 one end projecting through the front of the case and means at the opposite end to throw the winding mechanism out of gear for temporarily stopping and continuing the music, whereby short stops or pauses in the music 15 being played may be produced, substantially as described.

12. In an automatic attachment for pianos, the take-up roller provided with the friction-pulley 45, combined with sheet-winding mechanism, comprising the swinging shaft 47 having 20 a driving-pulley at one end and at its swinging end provided with the pulley 46 engaging the pulley 45 on the winding-roll, a pivoted lever 58 provided with means extending 25 outside of the casing to move said lever to cause it to impinge between a friction-roller on the frame and the swinging shaft, to thereby disengage the pulleys 45 and 46 to stop the winding, and means for reengaging 30 said pulleys when the lever is withdrawn or released, substantially as described.

13. In an automatic attachment for pianos, the combination with the keyboard-operating devices, constructed as composite fingers, each 35 comprising a series of levers 1, 2 and 3, flexible connections therefor, and means for operating said composite fingers, of an expression-bar arranged above the levers 2, and a finger-piece connected to said expression-bar extending 40 through the front of the casing, whereby said expression-bar may be adjusted with relation to the levers 2 to limit the movement of said levers, and a sliding lock provided with an inclined surface adapted to engage and support 45 the finger-piece to hold the expression-bar in its adjusted position, substantially as described.

14. In an automatic attachment for pianos, the stop 57 having means connected therewith 50 which, when the said stop is moved longitudinally, will effect the stopping and starting of the sheet-winding mechanism, and when moved laterally, will throw into operation the rewinding mechanism, substantially as described.

15. In an automatic attachment for pianos, the stop 57 having means connected therewith which, when the said stop is moved longitudinally will effect the stopping and starting 60 of the sheet-winding mechanism, and when moved laterally, when pushed in, will throw into operation the rewinding mechanism, and means to prevent lateral movement of the said

stop when it is pulled out to effect the starting of the sheet-winding mechanism, substantially 65 as described.

16. In an automatic attachment for pianos, the combination with a cylinder provided with a cork surface, of a series of shoe-levers provided with cork-faced shoes adapted to be 70 brought into contact with the said cylinder, and a series of keyboard-operating devices constructed as composite fingers consisting of the levers 1, 2 and 3, and a spring 5, having one end secured to the lever 2 and the opposite end secured to the lever 3, substantially 75 as described.

17. In an automatic attachment for pianos, the combination with the sheet-winding mechanism and the take-up roller, of a rod having 80 one end projecting through the case and adapted to throw the sheet-winding mechanism out of gear with the take-up roller, when pushed in, for temporarily stopping the travel of the music-sheet, whereby short stops or 85 pauses in the music being played may be produced.

18. In an automatic attachment for pianos, the combination with the sheet-winding mechanism and the take-up roller, of a rod having 90 one end projecting through the case and means at the opposite end which when the said rod is pushed in will stop the take-up roller without stopping the sheet-winding mechanism, whereby short stops or pauses may be produced. 95

19. In an automatic attachment for pianos, the combination with the sheet-winding mechanism and the take-up roller, of a rod having one end projecting through the case and means 100 at the other end which when the said rod is pushed in will stop the take-up roller; and means to return the said rod to its normal position when released by the operator, whereby short stops or pauses in the music being played 105 may be produced.

20. In an automatic attachment for pianos, the combination with the sheet-winding mechanism, including the take-up roller, of a stop projecting through the front of the case and having means connected therewith which, when the said stop is pushed in, will temporarily disconnect the take-up roller from its source of propulsion so long as the stop is held pressed in, and means for returning the said 115 stop to its normal position when released to allow the take-up roller to again come into connection with its source of propulsion, as and for the purpose described.

In testimony whereof I affix my signature in 120 the presence of two witnesses.

JOHN A. SMITH.

Witnesses:

CHAPIN A. FERGUSON,
WILMER EMORY.
